INVENTOR.
WILLIAM E. ELLIOTT.

BY
Sylvanne H. Collier,
ATTORNEY

UNITED STATES PATENT OFFICE.

WILLIAM E. ELLIOTT, OF LYNN, MASSACHUSETTS.

BOX.

Application filed April 6, 1921. Serial No. 458,985.

To all whom it may concern:

Be it known that I, WILLIAM E. ELLIOTT, a citizen of the United States, residing at Lynn, in the county of Essex and State of Massachusetts, have invented a new and useful Box, of which the following is a specification.

A well-known form of packing box consists of a tube or, as it is often termed, a funnel, formed of a strip of pasteboard having its ends secured together, the strip being creased or bent to furnish rectangular edges. Into this funnel are forced opposite ends or heads, each head having provided along its edges flanges corresponding to the sides of the funnel, and being respectively secured to said sides by staples to complete the closure. While such boxes are relatively light, strong and inexpensive, the structure includes three distinct elements, which when stored or shipped flat must be brought together to be assembled; they present some difficulties in associating the heads with the funnels in getting the flanges to register properly with the ends of the funnel in preparation for inserting the fastenings; and when the box is opened, one of the heads is naturally cut or otherwise separated from the body, leaving no convenient cover. These objections the present invention overcomes without material increase in the cost of the box and without sacrificing its other advantages.

The invention resides in the various combinations and relations hereinafter described and particularly claimed.

One of several embodiments which my invention may assume is illustrated in the accompanying drawing, in which Figure 1 shows my improved box knocked down, but with the sides of the funnel somewhat separated, as in starting the step of forming the box to receive its contents; and Fig. 2 shows in perspective the box set up, with one of the ends free at three of its edges to serve as a cover.

The tubular funnel furnishing the four side walls 10 of my improved box, which walls meet at the edges 11, these being rectangular in the completed box, is formed from a strip of pasteboard or like suitable material, with its ends overlapped and secured by a row of staples 12 or other fasteners. Each of the opposite heads or end walls 13 has, at three edges, flanges 14 formed by bending said edges along lines 15 produced by indentations or otherwise

weakened portions impressed in the material of the head. At the fourth edge of each head the flange is longer than those of the associated edges, including an inner portion 16 bent upon a line 17 between the flange and the body of the head, and an outer portion 18 divided from the flange-portion 16 by a weakened line 19. The lines 17 and 19 are so impressed in the head material that the flanges naturally bend in opposite directions.

In preparation for the assembling of the box, the flange-portions 18 may be secured to the inner surface of each end of opposite sides of the walls 10 of the funnel by a row of staples 20, the position of the flange-portions 18 being such that the lines 19 practically coincide with the edges of these walls 10. To complete the closure, the heads 13 are turned in about the flange-portions 16 and 18 as hinges, the indented line 19 being at the axis of the hinge, until the head lies just within and at right angles to the side walls 10, with the outer edges of the flanges 14 situated in the plane of the ends of the funnel and the flange-portions 16 and 18 parallel to each other. When thus located, rows of staples 21 may be driven through the flanges 14 and walls 10, thus fastening the heads securely. When it is desired to obtain access to the contents of the box thus closed, the staples 21 may be withdrawn from the flanges 14, leaving the row 20 through the flange-portion 18 still in place. The opposite head, which may now be considered the bottom of the box, is left undisturbed. This furnishes, at the end from which the staples are removed a cover hinging about the flange-portions 16 and 18, which may be either turned down until it fits within the funnel-end to give a complete closure, or may be swung upwardly and outwardly about its hinge to fully free the top of the box to expose its contents.

This box may be sent out from the factory to the purchaser with the heads attached by the staples 20, as in Fig. 1 of the drawing, the structure being complete as a unit, with no unsecured parts, and with which one needs only to open or expand the funnel and bend the heads into position about their hinges and fasten them to furnish a closed box. In doing this, since these heads are already secured by their flange-portions 18 in correct relation to the funnel walls, the other flanges 14 of these heads slip easily and in

proper alinement into place in the funnel, there being little possibility of inserting them too far or irregularly in preparation for the insertion of the staples 21. In its flat or knocked-down form, the side walls 10 lie in pairs parallel to each other, and the presence of the heads, which are folded outwardly parallel to the side walls as a part of the unit structure, adds little to its bulk, and 10 since the heads fold upon opposite sides of the collapsed funnel, they by no possibility interfere with each other.

I claim:

- 15 1. A box comprising side walls and a co-operating end wall having at one edge a double flange, and means for securing one of said flanges to a side wall while leaving the associated flange free to move with relation to the wall.
- 20 2. A box comprising side walls and a co-operating end wall having at one edge a double flange consisting of inner and outer portions, and means for securing the outer flange-portion only to a side wall.
- 25 3. A box comprising side walls and a co-operating end wall having at one edge a double flange consisting of inner and outer portions, and means for securing the end wall in place between the side walls with 30 the portions of the double flange normally extending parallel to each other but being free to move relatively.
- 35 4. A box comprising side walls and a co-operating end wall having at one edge a double flange consisting of inner and outer portions, the meeting lines between the flange-portions and between the inner flange-portion and the side wall being arranged to cause the flanges to bend in opposite directions, and means for securing the outer flange-portion only to a side wall.
- 40 5. A box comprising side walls and a co-

operating end wall having at one edge a double flange and at the outer edges single flanges, and means for securing the single flanges and the outer portion only of the double flange to the side walls.

45 6. A box comprising side walls and a co-operating end wall having at one edge a double flange and at the other edges single flanges, and staples securing the single flanges and the outer portion of the double flanges to the side walls, the inner portion of the double flange being free from the staples.

50 7. A folding knock-down box comprising side walls secured to one another to form a tube and arranged to fold at their junctions to bring said walls into parallel relation while thus secured, and end walls each attached at one edge to a side wall and arranged to fold outwardly parallel to said side walls.

55 8. A folding knock-down box comprising side walls connected to form a tube and arranged to fold at their junctions to bring said walls into parallel relation, end walls each having at one edge a double flange, and means for securing the outer portion of the flanges to opposite ends of the opposite side walls, said end walls being arranged to bend outwardly parallel to the side walls.

60 9. A folding box comprising side walls secured to one another to form a tube and arranged to fold at their junctions to bring said walls into parallel relation while thus secured, and end walls attached to and arranged to lie upon the folded side walls and to fit within the tube when said side walls are opened.

65 Signed at Boston, in the county of Suffolk and State of Massachusetts, this 29th day of March, 1921.

WILLIAM E. ELLIOTT.
